UNITED STATES PATENT OFFICE.

DE WITT C. PRESCOTT, OF CHICAGO, ILLINOIS.

BALANCED VALVE.

SPECIFICATION forming part of Letters Patent No. 730,699, dated June 9, 1903.

Application filed April 3, 1903. Serial No. 150,880. (No model.)

To all whom it may concern:

Be it known that I, DE WITT C. PRESCOTT, a citizen of the United States, and a resident of Chicago, county of Cook, and State of Illinois, have invented certain new and useful Improvements in Balanced Valves, of which the following is a specification and which are illustrated in the accompanying drawings, forming a part thereof.

10 The invention relates to engine-valves, and particularly to that class of single-acting valves used in connection with direct-steam-feed motors for sawmill-carriages.

15 The object of the invention is, primarily, to eliminate in valves of this character what is known in the trade as the "kick-back," being a more or less vicious jerk of the valve immediately following its initial movement, particularly on a quick reversal of the motor, and causing a jar to the hand of the operator.

20 A further object is to provide a complete balance of a valve of this character.

25 The invention consists in the structure hereinafter fully described, and illustrated in the accompanying drawings, in which—

30 Figure 1 is a detail of a sawmill feed-motor. Fig. 2 is a longitudinal central section of the valve through its cylinder and exhaust ports. Fig. 3 is a longitudinal central section on a plane perpendicular to that of Fig. 2, and Fig. 4 is a transverse section of the valve on the line 4 of Fig. 2.

35 The valve-casing is represented in Figs. 2 and 3 as without heads.

In motors of the type referred to a cylinder, as 24, is employed, which is as long as the range of travel of the carriage it is intended to drive, and this cylinder is provided with a 40 piston (not shown) having its rod 25 attached directly to the sawmill-carriage, as shown at 26. Usually such a motor is provided with two valves, as 10 and 23, one at each end, which are controlled by a single hand-lever, 45 as 27, suitably located. Each of these valves serves one end only of the cylinder, and consequently is what is known as a "single-acting" valve.

50 The valve-casing 10 is preferably cylindrical in form and may or may not be provided with heads, as 11 12. This casing is

provided with an induction-port 13, an exhaust-port 14, and a cylinder-port 15, arranged in the order named and each port opening to the chamber of the valve-casing 55 annularly or, in other words, each port being continued in the inner face of the valve-chamber by means of an annular channel, thereby providing for a complete lateral balancing of the valve as well as for large port 60 area.

The valve proper, 16, is preferably in piston form and has a peripheral cavity 17 of sufficient length to so far overlap the three ports that it is in constant register with the 65 cylinder-port 15. A face-ring 18—that is to say, a ring which forms part of the peripheral face of the valve—crosses the cavity 17 intermediate of its ends and is carried by longitudinal ribs 19, rising from the bottom 70 thereof and extending, if desired, the entire length of the cavity, as shown. The ring 18 is of sufficient width to approximately span the induction and exhaust ports simultaneously and is spaced apart from the end of the cavity 75 17 adjacent to the induction-port 13 a distance substantially equal to the width of the channel forming a continuation of that port, and the distance between the exhaust and cylinder ports is such that the face-ring 18 80 does not materially encroach upon the cylinder-port when the induction-port is open. When the valve-casing is provided with heads, as 11 and 12, ducts 20 21 lead from the exhaust-port to the opposite ends of the casing, 85 so as to provide a perfect endwise balance of the valve and for the drainage of any water of condensation which may accumulate within the casing.

In the structure described the cylinder-port 90 15 being constantly in register with the cavity 17 of the valve 16 there is at all times the same pressure within the valve-cavity as within the cylinder. As the valve is moved to open the induction-port the steam enters 95 the valve-cavity through a narrow slit, and it is supposed by some that the kick is due to what might be called a "wedge" action of the steam tending to widen this slit.

The valve herein described is so constructed 100 that as the induction-port begins to open and the thin sheet of steam rushes into the valve-

cavity it impinges against the end wall of this cavity, so that its impact offsets the so-called "wedge" action just referred to.

I do not undertake to advance a definite theory as to the action by which the valve herein described eliminates the objectionable kick, but believe it to be due either to the continuous communication of the valve-cavity with the cylinder-port or to the described arrangement of the induction-ports of casing and valve or to both combined.

The valve is shown in Figs. 2 and 3 as in its central position—that is to say, with the motor stopped—and preferably, as is shown, the exhaust-port is slightly open, so as to relieve the pressure upon the piston due to the expansibility of the steam and also provide for the drainage of the cylinder when it becomes cool.

It will be understood that the valves 10 and 23 are alike, except in that the one is the reverse of the other.

I claim as my invention—

1. In an engine-valve, a casing having an induction-port, a cylinder-port, and an exhaust-port between the other two ports, a reciprocating valve having a cavity overlapping the several ports, and a face-section crossing the cavity but spaced apart from its ends and of sufficient width to simultaneously cover the induction and exhaust ports.

2. In an engine-valve, a cylindrical casing

having induction, exhaust and cylinder ports opening annularly to its chamber, the exhaust-port being intermediate of the other two ports, a piston-valve reciprocating within the casing and having an annular cavity of sufficient width to overlap the several ports, and a face-ring crossing the cavity intermediate of its ends and of sufficient width to simultaneously cover the induction and exhaust ports.

3. In an engine-valve, a casing having induction, exhaust and cylinder ports arranged in the order stated, a reciprocating valve having a cavity overlapping the several ports and prolonged so that it is at all times in register with the cylinder-port, and a face-section crossing the cavity intermediate of its ends and of sufficient width to simultaneously cover the induction and exhaust ports.

4. In an engine-valve, a cylindrical casing having induction, exhaust and cylinder ports arranged in the order stated and opening annularly to the chamber of the casing, and a piston-valve having an annular cavity overlapping the several ports, and a face-ring crossing the cavity intermediate of its ends and of sufficient width to simultaneously cover the induction and exhaust ports.

DE WITT C. PRÉSCOTT.
